(57) **CLAIM**

The ornamental design for a weight lifting machine, as shown and described.

DESCRIPTION

FIG. 1 is a front perspective view from above of the weight lifting machine showing the new design; FIG. 2 is a front elevation view of the weight lifting machine of FIG. 1;

FIG. 3 is a rear elevation view of the weight lifting machine of FIG. 1;

FIG. 4 is a left side elevation view of the weight lifting machine of FIG. 1;

FIG. 5 is a right side elevation view of the weight lifting machine of FIG. 1;

FIG. 6 is a bottom plan view of the weight lifting machine of FIG. 1; and,

FIG. 7 is a top plan view of the weight lifting machine of FIG. 1.

1 Claim, 7 Drawing Sheets(56)
